UNITED STATES PATENT OFFICE.

FREDERICK C. ESMOND, OF BROOKLYN, NEW YORK, ASSIGNOR TO THE ESMOND ELECTRIC TRACTION AND SIGNAL CO., OF WEST VIRGINIA.

UNIT-MULTIPLE SYSTEM OF TRAIN CONTROL.

SPECIFICATION forming part of Letters Patent No. 670,897, dated March 26, 1901.

Application filed January 25, 1900. Serial No. 2,698. (No model.)

To all whom it may concern:

Be it known that I, FREDERICK CARLETON ESMOND, of 488 Fourth street, borough of Brooklyn, city of New York, county of Kings, 5 and State of New York, have invented a certain new and useful Improvement in Unit-Multiple Systems of Train Control, of which the following is a specification.

My invention relates to the control of the 10 speed and direction of motion of electrically-propelled vehicles, such as railway-cars, particularly when a number of such vehicles are connected to form a train, though certain of its features may be advantageously applied 15 to the operation of a single vehicle propelled by more than one motor.

As applied to a train of cars my invention involves the use of a set of conductors extending through each car and adapted to be 20 coupled between the cars, so as to form continuous working conductors throughout the train, car-propelling motors suitably connected therewith, and motor-controllers corresponding to the motors so connected and 25 arranged that while all the motors are controlled through the mechanical operation of a single controller, which may be any one of the controllers on the train, at the same time each of them is directly governed by the particular 30 resistance or controlling device corresponding thereto, all the controllers being made electrically effective through the operation of the controller which is for the time being the point from which the train is controlled. 35 To this end I divide the controlling devices employed, of whatever nature, whether simple rheostats, graded resistances, or the fields of the motors themselves, into sections, each of which is the equivalent of the corresponding 40 sections in all the controllers. The corresponding sections are connected in parallel between the train-conductors, so that when current is caused to pass through any section it will at the same time pass through all the corresponding sections, and the operation 45 of all the motors will be affected in the same manner and to the same extent. I also connect the motors to the train-conductors in groups or sets, with a controller corresponding to each group, the motors so arranged 50 that the same elements of corresponding mo-

tors in each group or set are permanently connected in parallel, while the circuit relations of the motors composing each group or set may be varied. In this way I am enabled 55 not only to control the operation of all the motors on a train from a single point by directly varying the rheostatic resistance in the motor-circuits, but also to directly effect a "series-parallel" control of the motors from 60 any one of the motor-controllers of the train, a result which under certain conditions of use is very desirable.

In the accompanying drawings, which illustrate embodiments of my invention, Figure 65 1 is a diagram of three cars, each carrying a single motor with simple rheostat-controllers. Fig. 2 is a diagram of the circuits of two cars with an arrangement for effecting the control of the motors through the fields thereof. Fig. 70 3 is a diagram showing the circuits of two cars with the control through the fields of the motors, parts of which are adapted to be in opposition to each other. Fig. 4 is a plan view of a car, showing the motors and controllers thereon. Fig. 5 is a diagram of the 75 circuits of two cars, showing two motors on each car, graded resistances, and a controller-switch on a single car adapted to control the motors on all the cars, and to change the connections of the motors on each car from a series to a multiple relation. Fig. 6 is a diagram illustrating the change in the circuit relations of a group of motors. Fig. 7 is a diagram showing an arrangement similar to 80 85 that shown in Fig. 5, but with resistances and a controller-switch on each car and such an arrangement of circuits that the motors on all the cars may be controlled from any car of the train. Fig. 8 is a diagram showing 90 the connections of a graded resistance for a freight-car. Fig. 9 shows an elevation of cable and two junction-boxes when two or more motors are used on one car. Fig. 10 shows elevation of cable and junction-box on cars 95 when there is one controller and rheostat or rheostat alone without controller. Fig. 11 shows side view of train with arrangement of controllers adapted to ordinary accommodation-train work. Fig. 12 shows a similar view 100 of a freight-train. Fig. 13 shows a side view of the arrangement of controllers on an ex-

press-train adapted to carry four motors on each car.

The same letters and figures of reference indicate corresponding parts throughout the drawings.

A A' are the railway-tracks, W W the car-wheels, and G a supply-conductor with which the current-collecting devices T T on the train make contact.

10 M M' are the car-propelling motors, having armatures E E' and fields F F'.

a b c d e, &c., are the contact-points of the controllers, C C' the controller-arms, and R reversing-switches.

15 The numbered wires 1 2 3, &c., are the conductors extending through the train, being united by couplings D, which may be of any usual or suitable construction, between the cars.

20 Referring to Fig. 1, simple rheostat-controllers are shown on three cars, the several sections of which are connected in multiple between the train-conductors 1 2 3 4 5. Assuming that the train is proceeding from left

25 to right and that the controller and reversing-switch in the forward car at the right are being used for the control of the train, the arms of the controllers and the reversing-switches on the other cars will be each turned

30 to a neutral point and the flow of current will be as follows: from current-collector T through wire H and controller-arm C to point d, upon which arm C is shown as resting, through the several sections of the controller to point a, 35 to arm e¹ of switch R, wire 6^a to conductor 6, to and through armature E to conductor 7, to wire 7^a, to arm e⁵ of switch R, wire 8^a, conductor 8, wire I, to and through field F, and to ground through the wire K, which is

40 connected to the axles of the car or to a return-conductor. Current also passes from the point d of the first controller through wire 4^a to and through conductor 4 to the second car of the train, to wire 4^a on the second car, to

45 point d of the controller on that car, through the controller-sections to point a, wire 1^a to conductor 1, back to the first car, wire 1^a to point a of the controller on the first car, by the same course as in the first instance to

50 wire 6, to and through the armature E' on the second car, through the conductor 7 to the first car, through wire 7^a, switch-arm e⁵, wire 8^a, conductor 8, back to the second car, to wire I', field F' on second car, and to ground. In

55 the same manner current passes through as many of the rheostat coils or sections on each car as are in circuit on the first or controlling car, and each motor is governed by its individual rheostat-resistance, the amount of which is determined on the controlling-car and is the same in all the motor-circuits.

In order to reverse the motors, the arms of the switch R on the controlling-car are moved from the contacts b⁵ c⁵ to the contacts 65 a⁵ b⁵, when the direction of current through one of the elements of each motor (in the pres-

ent arrangement the armature) will be reversed.

In the arrangement shown in Fig. 2 the fields of the several motors are divided into 70 sections, which are joined to the controller-points and connected in multiple between the train-conductors. The number of field-coils in circuit in each of the motors is determined by the position of the controller-arm C upon 75 the controlling-car and is the same in all the motors. The reversal of the motors in this car is effected by reversing the flow of current in the field-coils. For this two sets of controller contact-points are employed, and 80 the current flows through the field-coils which are in circuit in one direction when the controller-arm C is upon a point of one set and through the field-coils which are in circuit in the opposite directions when the controller-arm C is upon a point of the other set. The controller-arm is divided transversely into two parts C C', which are insulated apart, the part C' being adapted to make contact with plates C'' C³. The course of the current 85 is from the collector T through the connections E in multiple of the several motors to the arm C, the contact-point on which it rests, and to such of the field-coils of the several motors as correspond to this point, to the 90 train-conductor 1 or 10, according to the direction of the current, plate C'' or C³, as the case may be, arm C', and return-wire I. It will be evident that in reversing the motors current is first cut out from the fields step 100 by step from one direction and then cut in step by step from the other direction. If desired, a variable resistance may, as shown, be included in the motor-circuit.

In Fig. 3 is shown a modification of the arrangement shown in Fig. 2. In this case only a portion, as F', of each field is connected as described in connection with Fig. 2, the direction of current through the remainder F² of each field being constant. Thus a differential effect is produced, the current which flows through those sections of the part F' of each field which are in circuit either opposing or assisting, according to its direction, the current flowing through the part F². The 115 current passes from the collector T to controller-arm C and the controller-point on which arm C rests, and by the wire therefrom to that train-conductor to which such wire is connected, thence through the connected sections of the part F' of the field and the corresponding sections in the fields of all the motors through the wire 1^b or 5^b, according to the direction of the current, to one or the other of plates c¹ c⁵, thence by conducting-arm C', which is secured to the under side of arm C and insulated therefrom (see Fig. 3^a) to plate c⁶, thence by wire 6^a to conductor 6, through the part F² of the field, to conductor 7, and by switch R through the armatures in 120 multiple and to ground. The reversing of the motors is effected by

moving the reversing-switch R on the controlling-car to reverse the circuit through the armatures in the same manner as described in connection with Fig. 1.

5 The arrangement of the motors in sets or groups is illustrated in Figs. 5, 6, and 7. It may be most clearly described in connection with a single controller having a graded resistance adapted to be put in circuit with all 10 the motors on the train, an arrangement which in itself is particularly adapted to use on freight-trains. The numbered wires are the conductors extending through the train, between which are connected the elements of 15 the several motors. I regard each pair of motors M M' as a group the circuit connections of which may by means of the controller be varied from series to parallel. One or 20 more of such groups may be carried on each 25 car or vehicle. Corresponding elements of corresponding motors, as the fields F F of the motors M M', &c., are permanently connected in parallel between the same train-conductors. While I have illustrated in Fig. 5 for 30 the sake of simplicity a single resistance adapted to be connected in circuit with all the motors, the preferred arrangement is, as 35 shown in Fig. 7, a resistance or controlling device corresponding to each group of motors in the same manner as in the case of single motors. A resistance or controlling device corresponds to each, as shown in Figs. 1, 2, and 3.

The operation of the controller in varying 35 the resistance in circuit and changing the circuit relations of the motors is as follows: When the controller-arm is turned so that those circuit-closers on the controller-cylinder which reach the dotted line 1—viz., a' h' 40 i' k'—are in contact with the corresponding controller-points a h i k, the motor elements of each car will be in series, with the highest resistance cut in, as shown in diagram at 1, Fig. 6. The course of the current in this 45 case (the reversing-switch R being turned so that the circuit-closers a' b' c' d' are upon the corresponding points a' a' b' &c.) will be as follows: from collector T through wire H to 50 train-conductor 1, wire 1^a, contact a, circuit-closer a', thence to circuit-closer h', contact-point h, through the maximum resistance to point b, wire o, reverser contact-point a⁵, circuit-closer c', to contact a⁶, wire 2^a, to train-conductor 2, to and through armatures E of 55 the several motors M in parallel on all the cars, to conductor 3, to wire 3^a, contact b⁵, circuit-closer b⁴, contact b⁶, wire 4^a, conductor 4, to and through the fields F of the several motors M, to conductor 5, wire 5^a, to contact i, circuit-closer i', to circuit-closer k', contact k, wire p, to reverser-contact c⁵, circuit-closer c⁴, contact c⁶, wire 6^a, to conductor 6, to and through the armatures E' of the several motors M' in parallel between conductors 60 6 and 7, to conductor 7, wire 7^a, to contact d⁵, circuit-closer d⁴, contact d⁶, wire 8^a, to conductor 8, to and through the several fields F'

of the motors M', to conductor 9, and thence to ground or a return-conductor by wires I. The coils of the resistance are successively 70 short-circuited as the controller is moved, so as to bring others of the circuit-closers, as g' f', &c., on the line 2 in contact with the corresponding contact-points, as g' f', &c., until when all the circuit-closers on the line 2 are in contact with the contact-points the entire resistance will be short-circuited and the motors of each group will be in series with no resistance in circuit, as shown at 2 in Fig. 6. When the controller C is moved so as to bring 80 the circuit-closers l² m² in contact with the contacts l m, one of the motors of each group is temporarily cut out of circuit, and upon further moving the controller so that the circuit-closers j² k² are in contact with the contacts j k the motors are connected in "parallel" with the maximum resistance in circuit, 85 as shown at 3 in Fig. 6. In this case the current divides after passing through the resistance. A part follows the same circuit as 90 before through wire o and the armatures and fields of the motors M, and a part passes to contact j, circuit-closer j², circuit-closer k², contact k, wire p, contact c⁵, circuit-closer c⁴, contact c⁶, wire 6^a, to conductor 6, and then 95 to and through the armatures E' and fields F' of the motors M' in the same manner as before. Upon further moving the controller, so as to successively bring the circuit-closers on the line 4 upon the contacts, the coils of 100 the resistance will be successively short-circuited until the condition shown at 4, Fig. 6, is reached, when the motors are connected in parallel with no resistance. Upon moving the reversing-switch R, so that the circuit-closers e⁴ f⁴ e⁵ f⁵, &c., are in contact with the contact-points a⁵ a⁶ b⁵ b⁶, &c., the direction of 105 the current through one of the elements of each motor, in this case the armature, will be reversed under all the conditions specified. 110

As shown in Fig. 7, the arrangement of circuit for throwing the motors into series-parallel relation is the same as in Fig. 5; but a controller with a graded resistance is provided for each group of motors, and the corresponding sections of the several resistances are connected in parallel throughout the train, so that the motors of each group are controlled by the corresponding resistance, and the control of all the motors may be effected from 115 any car of the train.

From the foregoing it will be evident that by means of my invention I effect a considerable economy of wiring and provide for the efficient control of all the motors upon a train 125 of cars from any one of a number of controllers thereon and also secure the efficient control of the motors on a single vehicle carrying a plurality of motors, the advantages of which will be readily apparent to those skilled in 130 the art.

I have described my invention in connection with the operation of railway-trains, to which it is particularly adapted; but it

will be evident that it is usefully applicable to the operation of similarly-arranged motors, whether located upon other vehicles than railway-trains or upon fixed platforms, and I wish it understood that the claims are intended to apply to and cover the system of motor control wherever the motor may be located.

What I claim as new, and desire to secure by Letters Patent, is—

1. In a unit-multiple system of electrical train control, the combination of a plurality of car-propelling motors, a plurality of motor-controllers, means upon each of said controllers for qualifying the flow of current to the motor or motors corresponding thereto, and means for electrically connecting any given point of each of said controllers with the corresponding point of each of the other of said controllers, substantially as described.

2. In a unit-multiple system of electrical train control, the combination of a plurality of car-propelling motors, a plurality of motor-controllers, connections between corresponding points of the several controllers, means operable at any one of said controllers for controlling the flow of current to all the motors, and reversing-switches each of which is operable to reverse the flow of current through one of the elements of each of said motors, substantially as described.

3. In a unit-multiple system of electrical train control, the combination of a plurality of conductors, a plurality of motors having one of the elements of each divided into sections and corresponding sections of all said elements connected in parallel between said conductors, and means for simultaneously varying the number of sections through which current flows in all the motors, substantially as described.

4. In a unit-multiple system of electrical train control, the combination of a plurality of conductors, a plurality of car-propelling motors having one of the elements of each divided into sections and the corresponding sections in all said elements connected in parallel between said conductors, a plurality of motor-controllers, and means operable at any one of said controllers for varying the number of said sections through which current flows, in all the motors, substantially as described.

5. In a unit-multiple system of electrical train control, the combination of a plurality of conductors, a plurality of car-propelling motors having one of the elements of each divided into sections and the corresponding section of all said elements connected in parallel between said conductors, and means for simultaneously reversing the direction of current through all of said elements, substantially as described.

6. In a unit-multiple system of electrical train control, the combination of a plurality of conductors, a plurality of motors having one element of each divided into sections and

corresponding sections in all said elements connected in parallel between said conductors, means for simultaneously varying the number of said sections through which current flows in all said elements and means for simultaneously reversing the direction of current therein, substantially as described.

7. In a unit-multiple system of train control, the combination of a plurality of conductors, a plurality of car-propelling motors having one element of each divided into sections and the corresponding sections in all said elements connected in parallel between said conductors, and a variable resistance in series with said motors, substantially as described.

8. In a unit-multiple system of electrical train control, the combination of a plurality of conductors, a plurality of motors having one of the elements of each divided into sections and corresponding sections in all said elements connected in parallel between said conductors, means for simultaneously varying the number of said sections through which current flows in all said elements, and means for changing the direction of current in a part of said elements so that it may be either the same as or opposed to the direction of the flow of current through the remainder of such element, substantially as described.

9. In a unit-multiple system of electrical train control, the combination of a plurality of conductors, groups of car-propelling motors having their elements connected to said conductors, motor-controllers corresponding to said groups of motors, and means operable at any one of said motor-controllers for changing the circuit relations between the motors in each group, substantially as described.

10. In a unit-multiple system of electrical train control, the combination of a plurality of conductors, groups of train-propelling motors having the same elements of corresponding motors of the different groups connected in parallel between said conductors, motor-controllers corresponding to said groups of motors, and means operable at any one of said motor-controllers for changing the circuit relations between the motors in each of said groups, substantially as described.

11. In a unit-multiple system of electrical train control, the combination of a plurality of conductors, groups of car-propelling motors having the same elements of corresponding motors in the different groups connected in parallel between said conductors, motor-controllers each comprising a resistance corresponding to a group of motors and having sections adapted to be connected in parallel with the corresponding sections of the other resistances and in series with the group of motors to which it corresponds, and means operable at each of said controllers for varying the resistance in circuit with each group of motors, substantially as described.

12. In a system of electrical train control,

the combination of a plurality of conductors, groups of car-propelling motors having the same elements of corresponding motors in the different groups connected in parallel between said conductors, motor-controllers each comprising a resistance corresponding to a group of motors and having sections adapted to be connected in parallel with the corresponding sections of the other resistances and in series with the motors of the group to which it corresponds, and means operable at each of said controllers for varying the resistance in circuit with each group of motors and changing the circuit relations between the motors composing such group, substantially as described.

13. In a unit-multiple system of electrical train control, the combination of a plurality of conductors, groups of car-propelling motors having the same elements of corresponding motors in the different groups connected in parallel between said conductors, motor-controllers each comprising a resistance corresponding to a group of motors and having sections adapted to be connected in parallel with the corresponding sections of the other resistances and in series with the motors of the group to which it corresponds, means operable at each of said controllers for varying the resistance in circuit with each group of motors and changing the circuit relations between the motors composing such group, and reversing-switches each of which is adapted

to change the direction of the flow of current through all of said motors, substantially as described.

14. In a system of electrical train control, the combination of a plurality of motors, a plurality of controlling devices corresponding thereto, and a controller-switch for each of such controlling devices, the same being so connected and arranged that by the mechanical operation of any one of said switches all of said controlling devices will be made electrically effective to directly control the motors, substantially as described.

15. In a system of electrical train control, the combination of a plurality of conductors, groups of car-propelling motors having the same elements of corresponding motors in the different groups connected in parallel between said conductors, a resistance arranged to be put in circuit with all said motors, means for varying the resistance in circuit with the motors and means for simultaneously changing the circuit relations between the motors in each group, substantially as and for the purposes set forth.

In testimony whereof I have signed my name to this specification in the presence of two subscribing witnesses.

FREDERICK C. ESMOND.
